(57) **CLAIM**

The ornamental design for mount and holder combination for mobile devices, as shown and described.

DESCRIPTION

FIG. 1 is a front isometric view of a mount and holder combination for mobile devices showing our new design;

FIG. 2 is a front view of a mount and holder combination for mobile devices showing our new design;

FIG. 3 is a right side view of a mount and holder combination for mobile devices showing our new design;

FIG. 4 is a left side view of a mount and holder combination for mobile devices showing our new design;

FIG. 5 is a top view of a mount and holder combination for mobile devices showing our new design;

FIG. 6 is a front isometric view of a mount and holder combination for mobile devices showing our new design;

FIG. 7 is a front view of a mount and holder combination for mobile devices showing our new design;

FIG. 8 is a top view of a mount and holder combination for mobile devices showing our new design;

FIG. 9 is a right side view of a mount for a mount and holder combination for mobile devices showing our new design;

FIG. 10 is a left side view of a mount for a mount and holder combination for mobile devices showing our new design;

FIG. 11 is a bottom view of a mount for a mount and holder combination for mobile devices showing our new design;

FIG. 12 is a front isometric view of a mount and holder combination for mobile devices showing our new design, having the arm extended;

FIG. 13 is a front view of a mount and holder combination for mobile devices showing our new design, having the arm extended;

FIG. 14 is a top view of a mount and holder combination for mobile devices showing our new design, having the arm extended;

FIG. 15 is a right side view of a mount and holder combination for mobile devices showing our new design, having the arm extended;

FIG. 16 is a left side view of a mount and holder combination for mobile devices showing our new design, having the arm extended;

FIG. 17 is a bottom view of a mount and holder combination for mobile devices showing our new design, having the arm extended;

FIG. 18 is a front isometric view of a mount and holder combination for mobile devices showing our new design, having the arm extended and raised;

(Continued)

FIG. 19 is a front view of a mount and holder combination for mobile devices showing our new design, having the arm extended and raised;

FIG. 20 is a top view of a mount and holder combination for mobile devices showing our new design, having the arm extended and raised;

FIG. 21 is a right side view of a mount and holder combination for mobile devices showing our new design, having the arm extended and raised;

FIG. 22 is a left side view of a mount and holder combination for mobile devices showing our new design, having the arm extended and raised;

FIG. 23 is a front view of a mount and holder combination for mobile devices showing our new design, having the arm extended and raised;

FIG. 24 is a bottom view of a mount and holder combination for mobile devices showing our new design, having the arm extended and raised;

FIG. 25 is a front isometric view of a mount and holder combination for mobile devices showing our new design;

FIG. 26 is a front view of a mount and holder combination for mobile devices showing our new design;

FIG. 27 is a top view of a mount and holder combination for mobile devices showing our new design;

FIG. 28 is a bottom view of a mount and holder combination for mobile devices showing our new design;

FIG. 29 is a right side view of a mount and holder combination for mobile devices showing our new design;

FIG. 30 is a left side view of a mount and holder combination for mobile devices showing our new design;

FIG. 31 is a rear view of a mount and holder combination for mobile devices showing our new design;

FIG. 32 is a front isometric view of a mount and holder combination for mobile devices showing our new design, having the side two arms and the bottom two arms extended;

FIG. 33 is a front view of a mount and holder combination for mobile devices showing our new design, having the side two arms and the bottom two arms extended;

FIG. 34 is a rear view of a mount and holder combination for mobile devices showing our new design, having the side two arms and the bottom two arms extended;

FIG. 35 is a top view of a mount and holder combination for mobile devices showing our new design, having the side two arms and the bottom two arms extended;

FIG. 36 is a bottom view of a mount and holder combination for mobile devices showing our new design, having the side two arms and the bottom two arms extended;

FIG. 37 is a right side view of a mount and holder combination for mobile devices showing our new design, having the side two arms and the bottom two arms extended; and,

FIG. 38 is a left side view of a mount and holder combination for mobile devices showing our new design, having the side two arms and the bottom two arms extended.
